CHAIN SAW ATTACHMENT FOR OPERATING ROTATABLE TOOLS

Roland F. Kroll, Wautoma, Wis.

Application July 11, 1955, Serial No. 520,969

6 Claims. (Cl. 144—35)

This invention relates to an attachment or adapter unit for use with a conventional chain saw and whereby the chain saw, with the adapter unit applied thereto, may be utilized for accomplishing numerous operations such as drilling, circular sawing and clearing of undergrowth.

Another object of the invention is to provide an adapter unit or attachment for a circular saw whereby the adapter unit when applied to the circular saw and driven thereby may be utilized for supplying the motive power for pumps and other types of machinery.

A further object of the invention is to provide an adapter unit of extremely simple construction which may be quickly applied to or removed from a conventional chain saw without modification of the conventional structure of the saw.

Various other objects and advantages of the invention will hereinafter become more fully apparent from the following description of the drawings, illustrating presently preferred embodiments thereof, and wherein:

Figure 1 is a side elevational view of a conventional, portable type motor-driven chain saw with the adapter unit or attachment applied thereto;

Figure 2 is a top plan view thereof;

Figure 3 is an enlarged fragmentary substantially horizontal sectional view of the attachment or adapter unit and of a part of the chain saw, taken substantially along a plane as indicated by the line 3—3 of Figure 1;

Figure 4 is a fragmentary side elevational view illustrating a slightly modified embodiment of the outer end portion of the attachment or adapter unit;

Figure 5 (Sheet 1) is an enlarged fragmentary transverse sectional view, taken substantially along a plane as indicated by the line 5—5 of Figure 4, and

Figure 6 is a side elevational view, partly in section of a slightly modified form of the inner drive shaft of the adapter unit or attachment.

Referring more specifically to the drawings, for the purpose of illustrating a preferred application and use of the chain saw attachment or adapter unit, designated generally 8 and comprising the invention, a conventional motor-driven chain saw of the portable type is illustrated in the drawings. Said chain saw, designated generally 9, includes a gear housing 10 mounted on the forward end of the motor casing 11 and containing gearing, not shown, by means of which the drive shaft 12 (Fig. 3) of the saw 9 is driven from the motor, not shown, contained within the casing 11. The shaft 12 extends laterally from the inner side wall 13 of the gear housing 10 and has a driving sprocket wheel 14 fixed thereto, outwardly with respect to said inner wall 13. The shaft 12 is threaded, as seen at 15, beyond the sprocket wheel 14.

A chain supporting and guiding plate or blade 16 is supported on the inner housing wall 13, forwardly of the sprocket wheel 14, and extends forwardly therefrom a substantial distance. The plate 16 is disposed substantially in alignment with the sprocket wheel 14. An endless saw chain 17 of conventional construction slid-

2

ably engages the grooved periphery 18 of the plate 16 in a conventional manner and is trained around and driven by the sprocket wheel 14. The plate 16 adjacent its outer end is provided with an opening 19. The parts 5 through 19 of the saw 9 constitute no part of the present invention but have been illustrated and briefly described merely to afford a better understanding of the adapter unit or attachment 8.

Referring to Figures 1, 2 and 3, the adapter unit or attachment 8 includes a shaft 22 having an internally threaded recess 23 which is axially disposed with respect to said shaft and which opens outwardly of the inner end of the shaft and is provided with a surrounding flange 24. The recessed shaft end 23 engages the threaded end 15 of the drive shaft 12 for coupling the adapter shaft 22 to the drive shaft 12 for rotation therewith. The connection of the threaded parts 15 and 23 is such that when the drive shaft 12 is revolved in its normal direction of operation, rotation thereof will tend to tighten the threaded connection 15, 23. A disk 20 is fixed to the shaft 12 between the sprocket wheel 14 and the threaded shaft end 15. Setscrews 21 extend threadedly through the flange 24 and are advanced to bear against the outer side of the disk 20 to limit the extent that the shaft end 15 can be screwed into the recess 23. A V-belt pulley 25 is mounted on the adapter drive shaft 22 adjacent its outer end or outwardly with respect to the connection of the shaft 22 and the drive shaft 12. The pulley 25 has a hub 26 projecting laterally from one side thereof into which a setscrew 27 is threaded. The setscrew 27 is tightened against the shaft 22 for securing the pulley 25 to said shaft 22 for rotation therewith.

The adapter unit or saw attachment 8 also includes a substantially cylindrical bearing housing 28 having an open outer end 29 and an inner end wall 30 at the opposite, the inner end thereof. Said end wall 30 is provided with a central outwardly projecting annular hollow extension or flange 31 at least the outer end portion of which is externally threaded, as seen at 32 in Figure 3. Said extension or boss 31 is sized to pass slidably through the plate opening 19 and a nut 33 engages the threaded portion 32 thereof and is advanced against the plate 16 for securing the bearing housing 28 detachably to said plate. The bearing housing 28 extends outwardly from the same side of the plate 16 as the adapter shaft 22. The bearing housing 28 contains two annular antifriction bearing units 34 and 35 and an annular spacer 36 which is interposed between said bearing units. The bores of the bearing units 34 and 35 and the spacer 36 are disposed in alignment with and are of the same size as the bore of the hollow extension or boss 31.

A shaft 37, constituting the driven shaft of the adapter unit 8, has a portion thereof extending through the bearing units 34 and 35 and spacer 36 and which is journaled in said hollow extension or boss 31. Said end of the shaft 37 is provided with a restricted threaded stem 38 which extends outwardly from the boss 31 and on which is mounted a nut 39 and a washer 40. The nut 39 threadedly engages the stem 38 and the washer 40 is disposed on the stem between said nut and the adjacent end of the shaft 37 and the outer end of the boss 31. The other end portion of the shaft 37 extends a substantial distance outwardly with respect to the open end 29 of the bearing housing and is shown terminating in a threaded end 41. A V-type belt pulley 42 is mounted on the shaft 37 between the bearing housing 28 and the threaded shaft end 41. The pulley 42 has a hub 43 on the outer side thereof into which a setscrew 44 is threaded radially against the shaft 37 for securing the pulley 42 immovably to said shaft. A spacing collar or sleeve 45 is disposed on the shaft 37 between the pulley

42 and the outermost adjacent bearing unit 35. The sleeve 45 cooperates with the nut 39 and washer 40 to retain the shaft 37 against sliding movement relative to the bearing housing 28 and plate 16 and said parts have a sufficient loose engagement with the bearing unit 35 and the outer end of the boss 31 to permit the shaft 37 to rotate freely within the bearing housing. A conventional chuck 46 has a threaded socket 47 in its inner end to receive the shaft end 41 for detachably connecting the chuck to the shaft 37. The pulleys 25 and 42 are disposed substantially in alignment and are connected by an endless V-belt 48.

From the foregoing it will be readily apparent that when the drive shaft 12 of the sprocket wheel 14 is driven in a conventional manner so that the saw chain 17 will be driven by the sprocket wheel 14 to travel around the periphery of the plate or guide 16, that the driven shaft 22 of the adapter unit 8 will be rotated simultaneously with the drive shaft 12 of the saw due to its connection thereto, as previously described. The driven shaft 37 of the adapter unit or attachment 8 will be driven in unison with the drive shaft 22 by its connection thereto through the belt 48 and the pulleys 25 and 42 for causing the shaft 37 to rotate in the bearing housing 28. Any suitable element to be driven, as for example a drill bit 49, may be mounted in a conventional manner on the outer end of the chuck 46 to be rotated with said chuck and the driven shaft 37. The threaded connection 41, 47 is arranged whereby rotation of the shaft 37 will tend to tighten the shaft end 41 in the socket 47. It will also be apparent that other elements to be rotated may be secured in the chuck 46, so that the attachment unit 8, utilizing the chuck 46, may be used for driving pumps and various machinery.

Figures 4 and 5 illustrate a slightly modified form of the attachment, wherein the chuck 46 is omitted. In lieu thereof, as illustrated in Figure 5, a pair of nuts 50 are detachably mounted on the threaded shaft end 41 and a pair of clamping collars 51 are detachably mounted on the shaft end 41, between the nuts 50. A conventional circular saw blade 52 may be detachably mounted on the shaft portion 41 and secured thereto by tightening of the nuts 50 for clamping the hub portion of the blade 52 between the collars 51. It will also be readily apparent that other types of tools or implements may be mounted on the shaft 37 by means of the nuts 50 and collars 51. It will likewise be apparent that the circular saw blade 52 could be mounted against the outer end of the chuck 46.

Figure 6 illustrates a slightly modified form of the adapter drive shaft, designated generally 22a, and which differs from the shaft 22 in that the outer portion thereof is threaded, as seen at 53, to permit attachment of a belt pulley thereto by a threaded connection.

Various other modifications and changes are contemplated and may obviously be resorted to, without departing from the spirit or scope of the invention as hereinafter defined by the appended claims.

I claim as my invention:

1. In combination with a portable type power-driven chain saw including an elongated chain guiding plate about which the endless saw chain travels, said plate having an opening adjacent an outer end thereof, and a primary drive shaft disposed beyond the inner end of the guide plate and crosswise thereof on which drive shaft a sprocket wheel for driving the chain is secured; an adapter unit comprising an adapter drive shaft fixed to and extending outwardly from an outer end of said

primary drive shaft, an elongated housing having a hollow annular extension at one end thereof of reduced diameter relative to said housing extending through said guide plate opening, means securing said housing detachably to the guide plate with the axis of the housing disposed substantially parallel to the axis of the adapter drive shaft, a driven adapter shaft journaled in said housing independent of said chain and its bearing on the outer end of said guide plate and having an end portion extending from the end of the housing disposed remote from said guide plate, means supported by said end of the driven shaft, remote from the housing, and adapted to be attached to an implement to be driven by said adapter unit, and means forming a driving connection between the adapter drive shaft and driven adapter shaft of said adapter unit.

2. In an adapter unit as in claim 1, said means forming a driving connection between the adapter drive shaft and driven adapter shaft of the adapter unit comprising belt pulleys fixed to said shafts and an endless belt trained over and forming a driving connection between the belt pulleys.

3. In an adapter unit as in claim 1, said primary drive shaft having a threaded outer end, said adapter drive shaft having a threaded recess opening outwardly of an inner end thereof for threadedly engaging the outer end of the primary drive shaft, a collar fixed to the primary drive shaft between its threaded outer end and the sprocket wheel, the inner end of the adapter drive shaft having a flange extending outwardly therefrom, and set-screws extending threadedly through said flange and bearing against said collar for limiting the extent that the adapter drive shaft can be threaded onto the outer end of the primary drive shaft.

4. In an adapter unit as in claim 1, said housing having an outer open end disposed remote from said guide plate and the hollow extension thereof, a pair of annular anti-friction bearing units disposed in said housing and in which said driven adapter shaft is journaled, and an annular spacing member disposed in said housing between said bearing units and through which said driven adapter shaft loosely extends.

5. In an adapter unit as in claim 4, and a spacing collar disposed on said driven adapter shaft between the open end of said housing and a portion of said drive means and bearing against one of said bearing units.

6. In an adapter unit as in claim 5, said hollow extension having an externally threaded terminal portion, a nut threadedly engaging said terminal portion and abutting against one side of said guide plate for detachably securing the housing to the plate, said driven adapter shaft having a restricted threaded stem projecting from its opposite end and extending outwardly from the outer end of said hollow extension, a nut threadedly engaging said stem, and a washer disposed on said stem between the nut and the outer end of said threaded extension and cooperating with the nut and said spacing collar for detachably mounting the driven adapter shaft rotatably in said housing.
